W. B. CONAWAY & C. L. STEVENS.
PHOTOGRAPHIC PRINTING APPARATUS.
APPLICATION FILED JULY 29, 1908.

918,509.

Patented Apr. 20, 1909.

UNITED STATES PATENT OFFICE.

WILLIAM B. CONAWAY AND CARROLL L. STEVENS, OF AURORA, INDIANA.

PHOTOGRAPHIC-PRINTING APPARATUS.

No. 918,509.

Specification of Letters Patent.

Patented April 20, 1909.

Application filed July 29, 1908. Serial No. 445,912.

To all whom it may concern:

Be it known that we, WILLIAM B. CONAWAY and CARROLL L. STEVENS, citizens of the United States of America, and residents 5 of Aurora, county of Dearborn, and State of Indiana, have invented certain new and useful Improvements in Photographic-Printing Apparatus, of which the following is a specification.

10 Our invention relates to improvements in photographic printing apparatus.

One of its objects is to provide a convenient means for printing photographs by artificial light, to secure uniform prints, and to 15 avoid waste of material.

Another object is to provide an improved arrangement and means for regulating the light.

Another object is to provide improved 20 means to regulate and vary the time of exposure of the prints, and register the number of prints made.

Another object is to provide improved 25 means to turn on and off the light and stop the registering apparatus after the prints have received sufficient exposure, or when the apparatus is not in use.

It further consists in certain details of 30 form, combination and arrangement, all of which will be more fully set forth in the description of the accompanying drawings, in which:

Figure 1 is a front elevation of our improved apparatus. Fig. 2 is a section on line 35 $v-v$ of Fig. 1. Fig. 3 is a diagram of the electrical switches and wiring connecting the lights and motor and switches in circuit. Fig. 4 is a sectional detail view of the friction clutch. Fig. 5 is an enlarged detail of 40 the register, indicating the number of prints produced. Fig. 6 is a side elevation of a modification of the transmitting mechanism.

In the accompanying drawings, A, represents a frame or cabinet, within which is contained the apparatus and mechanism. In the front of the cabinet we provide one or more openings, or windows, A', to receive the ordinary photographic printing frames, which are seated therein facing inwardly, 50 and may be held in place by spring latches, a . We also preferably provide springs, a' , to bear on the upper edge of the printing frames to assist in throwing the frames outwardly when the latch a is opened. Arrangement is also made to receive and retain plates 55 of ground glass, a^2 , in front of the printing

frames, which plates, a^2 , may be removed and replaced as required. The ground glass serves to diffuse the light evenly over the prints. The artificial light is obtained from 60 a series of incandescent electric lights, B, the rear or base portion of the globes of said lights being silvered or mirrored to reflect the light toward the printing frames. The number of lights used will depend upon the 65 size of the prints it is desired to produce. The respective lights are separated from each other by partitions, b , of approximately the same depth as the length of the light globes, so that the light from each globe is 70 directed toward that portion of the printing frame directly in front of the globe, and prevented from striking upon other parts of the printing frame at undesirable angles.

Each incandescent light has a separate circuit, which is controlled by one of the switches, C, by means of which switches, C, and desired number of said lights may be cut into or out of circuit, the combination of lights being arranged to correspond with the requirements of the particular negative in use, and varied, if required, with each change of negative.

C' represents the main switch between the line and the lights and motor in the cabinet A. The bench, or table, A², of cabinet, A, is provided with a panel of ruby or orange glass, a^4 , which is illuminated from the underside by an incandescent light, a^5 , so that by placing the printing frame over the 85 panel, a^4 , the operator is enabled to arrange a fresh sheet of sensitized paper in proper position over the negative and to close the printing frame thereon. If desired, a panel of white glass may be used and a globe of 90 colored glass over the electric light.

We operate the mechanism controlling the lights, and timing and registering the prints, preferably by means of a small electric motor D of shunt type. Motors of the shunt 100 type will run at substantially a uniform number of revolutions per minute, and by means of a train of gears d , d' , d^2 , d^3 , d^4 , d^5 , d^6 , d^7 , commencing with gear, d , on the motor shaft and terminating in gear, d^7 , loosely 105 mounted on the shaft, E, the speed of gear, d^7 , is reduced to one revolution per minute. The shafts, d^8 , carrying the respective gears, d' , to d^6 , are journaled in brackets, d^9 , attached to the inside of cabinet, A. The shaft 110 E, has splined thereto a disk, e , which is held in frictional engagement with gear, d^7 , by

means of a spring, e' , pressing at its opposite end upon a collar locked to the shaft, E. A crank arm or lever, F, is rigidly attached to the end of shaft, E, outside the cabinet, A, the free end of the lever, F, being adapted to travel over a dial, f, divided to indicate fractions of a minute.

G, represents a rock shaft journaled at the zero point on dial, f, and provided outside 10 the cabinet with a crank arm, g, and pin, g' , which pin is adapted to be engaged by the lever, F, to rock shaft, G, in one direction, while a spring g^2 , tends to rotate shaft, G, in the opposite direction. Inside the cabinet, 15 A, the shaft, G, carries an electrical switch lever, H. One end of lever, H, is adapted to make electrical contact with the contact bar, h. The opposite end of lever, H, makes electrical contact with the contact bar, h' , to 20 break or establish a current from bar, h, to bar, h' , and through such of lights, B, as have their circuits closed at the switches, C. A pointer, i, moving over dial, I, on the table, A², serves to register the number of prints 25 which have been taken from the respective negatives. The pointer, i, is actuated by means of a ratchet wheel, J, within the cabinet, and fixed to the stem of pointer, i, which ratchet wheel is moved forward one space at 30 each movement of rock shaft, G, by means of a pawl, J', carried by rock shaft, G, the wheel J being prevented from moving backward by a pawl J².

In operation, the cabinet, A, being located 35 in a dark room, or room having a subdued, or ruby light, the switches, C, are adjusted to close the circuits of such lights, B, as may be required by the character of the particular negative to be treated. The sensitized paper 40 is placed with the negative, in the printing frame, while the printing frame rests over panel, A⁴. The printing frame is then secured in the opening, A'. The operator then grasps lever, F, and moves it to the left, 45 over dial f, to the point on the dial indicating the desired length of exposure to be given the print, causing disk, e, to slip on gear, d⁷. As soon as lever, F, is moved, the spring, g^2 , rocks shaft, G, causing switch 50 lever, H, to close the circuit through the lights, B, at the contacts, h, h' . The movements of the motor, D, through gears, d, to d⁷, and friction, e, slowly return the lever, F, to the normal position from which is was 55 moved by the operator. When lever, F, contacts with pin, g' , shaft, G, is rocked, thereby, in the opposite direction, breaking the circuit through the lights, B, whereupon the printing frame is detached, and a fresh sheet of 60 sensitized paper introduced. When a sufficient number of prints from one negative have been obtained, the operator turns pointer, i, by hand, to the zero position.

We preferably provide a plurality of windows, A', and duplicate sets of mechanism to

control the lights thereof, said duplicate mechanisms being geared to and operated in common by motor, D, while the slip of disks, e, permit both train of gears to run with the motor.

We provide a central partition, a⁶, in the upright portion of cabinet, A. We also prefer to hinge the sections through which windows, A', are pierced, so as to form doors, a⁷, a⁸, which permits said doors to be opened to 75 give access to the lights and to adjust the panels, a².

In the modification, Fig. 6, the shaft of motor, J', carries worms, k, k', at opposite ends. Said worms mesh with worm wheels, 80 k², k³, on shaft, E, which worm wheels correspond to gears, d⁷, of Figs. 1 and 2, and are of such ratio relative to the worms, as to make one revolution per minute. Motion is transmitted from the worm wheels to the 85 shafts, E', through friction clutches, as illustrated in Fig. 1.

The mechanism herein illustrated and described is capable of considerable modification without departing from the principle 90 of our invention.

What we claim is:

1. In a mechanism of the character indicated, a cabinet having an opening to receive a printing frame, a series of independent lights, each having a surrounding partition to intercept a portion of its rays to secure separate spheres of illumination and adapted when all in use to illuminate the face of a negative in the printing frame uniformly over its whole surface.

2. In a mechanism of the character indicated, a cabinet having an opening to receive a printing frame, a series of independent lights each having a shade to intercept a portion of its rays to secure separate and overlapping spheres of illumination and adapted when all in use to illuminate the face of a negative in the printing frame uniformly over its whole surface, and means to 100 separately control said lights so as to vary the intensity of illumination on different areas of the negative face.

3. In a mechanism of the character indicated, a cabinet having an opening to receive a printing frame, a series of independent lights to illuminate different sections of a negative carried by said printing frame, said lights being arranged in separate compartments and having separate and overlapping spheres of illumination, and means to 115 separately control said lights so as to vary the intensity of illumination on different areas of the face of a negative in the printing frame.

4. In a mechanism of the character indicated, a support to receive a printing frame, a series of lights arranged in front of said printing frame, said lights having shades to intercept a portion of the rays of each light 120

to create independent and overlapping spheres of illumination, and means to separately control said lights to vary the intensity of illumination on different areas of 5 the face of said printing frame.

5. In a mechanism of the character indicated, a support to receive a printing frame, a series of electric lights arranged in front of said printing frame, said lights having 10 shades to intercept a portion of the rays of each light to create independent and overlapping spheres of illumination and independently controlled circuits and mechanism actuated by the operator to establish a circuit 15 through the lights, and to automatically open circuits through the lights after the lapse of a predetermined period of time.

6. In a mechanism of the character indicated, a printing frame support, a series of 20 independent electric lights arranged in front of a printing frame, carried by said support, said lights being arranged in parallel circuit and having independent controlling switches, a switch common to the circuit of all the 25 lights adapted to be closed by the operator and to be automatically opened after the lapse of a predetermined length of time, and mechanism moving at a substantially uniform rate of speed to automatically open 30 said common switch to break the circuit through said lights.

7. In a mechanism of the character indicated in combination with a printing frame support and a series of independent electric 35 lights arranged in parallel circuit and in front of a printing frame carried by said support, and having independent controlling switches, an electric motor, a plurality of gears driven by said motor, a dial, a shaft 40 carrying a pointer, a friction clutch interposed between said shaft and said gears to yieldingly impart motion to said pointer, and means controlled by the movements of said pointer to close and automatically open 45 an electrical switch common to the circuits of all of said electric lights.

8. In a mechanism of the character indi-

cated a printing frame support, an electric light arranged to illuminate a printing frame carried by said support, an electric 50 motor, a clutch comprising a positively driven member receiving motion from said motor, and a member adapted to slide upon said positively driven member, a pointer shaft adapted to be intermittently driven by 55 said sliding clutch member, a pointer on said shaft, a dial over which said pointer is adapted to travel, a rock shaft adapted to be rocked by the motion of said pointer, an electrical switch controlling the circuit of 60 said electric light actuated by said rock shaft, and a pointer actuated by the movements of said rock shaft and adapted to indicate the number of prints produced.

9. In a mechanism of the character indicated, a cabinet comprising an upright section having a series of electric lights arranged in separate compartments, to have overlapping spheres of illumination, a door 70 in front of said lights, a ground glass detachably carried by said door, an opening in said door in front of said panel to receive a printing frame.

10. In a mechanism of the character indicated a cabinet comprising an upright section 75 having a series of electric lights arranged in a vertical plane and each provided with a shade to intercept a portion of the rays and create separate and overlapping spheres of illumination, a vertical door in 80 front of said lights, a ground glass panel detachably carried by said door, an opening in said door in front of said panel to receive a printing frame, a table section having a transparent panel, and means for illuminating the compartment beneath said table.

In testimony whereof, we have hereunto affixed our signatures, in the presence of two witnesses
